UNITED STATES PATENT OFFICE.

JAMES K. CLEARY, OF WASHINGTON, DISTRICT OF COLUMBIA.

BANK CHECK AND DRAFT.

SPECIFICATION forming part of Letters Patent No. 298,177, dated May 6, 1884.

Application filed April 6, 1883. Renewed March 27, 1884. (No model.)

To all whom it may concern:

Be it known that I, JAMES K. CLEARY, a citizen of the United States, residing at Washington, District of Columbia, have invented 5 new and useful Improvements in Bank Checks and Drafts, of which the following is a specification.

My invention relates to certain new and useful improvements in checks, drafts, and other 10 similar evidences of value.

The object of my invention is to provide a ready means for protection against alteration of the amount originally stated; and with this end in view my invention consists of a check, 15 draft, or other similar evidence of value printed in the usual form, to be filled up by the drawer, and, in addition, with a table of figures printed upon one end of the face of the check, or at any other desirable locality, said 20 table of figures consisting of five, or more or less, vertical columns—units, tens, hundreds, thousands, tens of thousands, &c.—from right to left in the usual order of enumeration, and each column reading vertically from top to 25 bottom from one to nine, with “indicator” and “arrester” characters, as will be herein-after more fully explained.

In order that others skilled may fully understand my invention, I will proceed to describe 30 the construction and mode of using the same, referring by letters to the accompanying drawing, which represents a plan view of the face side of an ordinary check with my improvement.

The usual form of printed matter and spaces 35 for filling amount is impressed upon the paper, as seen at A. A number-space is left at B, and a space for the amount in figures, with the dollar-sign, (\$), at C. At any suitable locality, 40 either upon the back or face of the check, but preferably the latter, I print a form such as shown at D, consisting of five vertical columns of figures reading from top to bottom from one to nine, and from right to left from units 45 to tens of thousands, in the usual order of enumeration, as clearly illustrated in the drawing, and on each side of the figures in each and every column I print indicators *a* and arresters *b*.

In using the check the amount for which it 50 is drawn is written in the usual space left for that purpose, and the figures corresponding

with the written amount are made at the left-hand corner at C, and then the figures printed at the point D are punched, as indicated by 55 the black dots—that is to say, the check illustrated in the drawing being drawn for four thousand eight hundred and twenty-nine dollars, the right-hand cipher of 40,000 is cancelled or punched out, leaving 4,000; the right-hand cipher of 8,000 in the next column to the right is canceled or punched out, leaving 800; the right-hand cipher of the 200 in the next column is canceled or punched out, leaving 20, and finally the right-hand cipher of 90 in 65 the next column is canceled or punched out, leaving 9; so that, reading from left to right, the amount indicated is 4,829; and from this illustration it will be readily appreciated that any desired amount can be indicated, and that 70 the amount so indicated is read in the usual manner from left to right. In the instance indicated the amount exhausts itself except as to cents. No provision is made for this purpose, because of lack of temptation to perpetrate a fraud. 75

In stating any amount in my table from \$1 to \$100,000 or more, said amount begins always in the extreme left-hand column and continues in the succeeding columns in regular order, 80 thus ignoring, if necessary, the ordinary arbitrary tabular arrangement of units, tens, &c. For instance, when stating a sum smaller than the extreme left-hand column calls for—say \$12—this amount would be indicated by punching out the third cipher from the right in 85 10,000 and the third cipher from the right in 2,000, which sum, exhausting itself, would not need the use of an arrester. So, also, should it be required to state \$120, then the second 90 cipher from the right in 10,000 and the second cipher from the right in 2,000 would be punched out, and the arrester at the end of 2,000 also punched out, to prevent the addition of any unit from 1 to 9. 95

In the instances cited the fifth and fourth columns only are used, thus, as already stated, ignoring the regular enumerative arrangement of the columns; but where it became necessary to use all of the columns in indicating 100 an amount, then the usual order of enumeration would be involved.

The characters placed before and after each set of figures, and which I denominate, re-

spectively, "indicators" and "arresters," are undisturbed in the instance shown in the drawing, but become necessary in cases where the enumeration of the amount to be indicated 5 requires less than four columns. For instance, suppose the amount to be indicated was \$45,300. Then the indicator in front of 40,000 is punched out, and the indicator in front of 5,000 is punched out, and the arrester at end 10 of 300 is punched out. This indicates that the enumeration ceases with the arrester. Where a single amount is indicated—as, for instance, \$80,000—the arrester at the end of 15 80,000 is punched out, which shows that the sum ends there. In this sum there is no necessity for the use of the indicator, as the arrester in closing the amount also indicates it.

The indicator and arrester characters may be of any arbitrary design—such as an arrow-head, hand, star, &c.—and the columns of figures may be arranged within any sort of border or design, without departing from the spirit of my invention.

It will be kept in mind that I use the extreme left-hand column for the initial figure, or beginning of any amount which it may be desired to indicate, and that in no instance will there appear more than one punch-hole 25 in any one of the vertical columns.

What I claim as new, and desire to secure by 30 Letters Patent is—

1. A check, draft, or other similar evidence of value, having imprinted upon it at any convenient locality a series of vertical columns of figures, the first arranged from top 35 to bottom from one to nine, indicating units, and the successive columns to the left of said unit-column representing multiples of one another by ten, in the usual order of enumeration, while each column increases vertically 40 in serial order, substantially as shown and described, whereby a given amount may be expressed and read from left to right in the usual manner, as hereinbefore set forth.

2. A check, draft, or other similar evidence 45 of value, having imprinted upon it a series of figures in vertical columns, and arranged horizontally in the order of usual enumeration, in combination with indicators and arresters, substantially as and for the purposes set forth. 50

In testimony whereof I have hereunto set my hand and seal in the presence of two subscribing witnesses.
